WILLIAM P. PARROTT AND JOHN J. BORDMAN, OF BOSTON, MASSACHUSETTS.

Letters Patent No. 65,593, dated June 11, 1867.

IMPROVED APPARATUS FOR AMALGAMATING AND COLLECTING GOLD AND SILVER FROM ORES.

The Schedule referred to in these Letters Patent and making part of the same.

TO ALL PERSONS TO WHOM THESE PRESENTS SHALL COME:

Be it known that we, WILLIAM P. PARROTT, and JOHN J. BORDMAN, of Boston, in the county of Suffolk, and State of Massachusetts, have invented a new and useful Machine for Extracting Metal from its Ore by means of mercury; and we do hereby declare the same to be fully described in the following specification and represented in the accompanying drawings, of which—

Figure 1 is a top view of the machine, without its cover and the chute thereof.

Figure 2, an elevation of one side of such machine.

Figure 3 is an elevation of the other side of the machine.

Figure 4 is an end view of it.

Figure 5 is a transverse section; and

Figure 6 a longitudinal section of the machine.

The plane of section of fig. 5 is through and in line of the axis of one of the amalgamating rollers (viz, that marked C) of the machine.

Figure 7 is a top view of the cover and its chute or induction spout.

Figure 8 is a top view of the duplex mercury-trough, and the scrapers at its ends.

In our machine we effect the amalgamation of the metal by means of one or more cylinders or rollers, one or more troughs of mercury, and one or more scrapers, or their equivalents, the purpose of the scraper or scrapers being to separate the amalgam from the curved surface or surfaces of the roller or rollers after its formation and accumulation thereon. In constructing the operative surface of each of such rollers we make it of brass, or some other metal or material for which mercury has an affinity, or to which it will readily adhere, so that while the roller or rollers may be revolving in the trough or against a surface having mercury on it, such mercury will adhere to and be taken up by the roller or rollers and be carried in contact with a mass of ore in a powdered state and mixed with water so as to be what is generally termed "ore pulp."

We usually combine with the said roller or rollers and trough or troughs a hopper and chute for supplying the ore pulp to the roller or rollers; and furthermore, we combine with the trough or troughs means of heating the same, and also what is termed a "riffle," viz, an inclined plane provided with a series of parallel ledges arranged on its upper surface.

Each or either of the cylinders or rollers we construct in the manner in which each of those of our ore-crushing machine, recently patented by us, is made, that is to say, we compose it of a series of peripheral segments or parts, a body, and devices or mechanism for fastening such peripheral segments to the body, the same being to enable such parts or segments to be renewed, or when worn to be removed from the body and others substituted for them.

Such a method of constructing each of the rollers we have represented in the aforementioned drawings, but as it is fully described in the specification of our said patent, which is dated January 8, 1867, and numbered 61,019, of United States Patents, and constitutes the subject of one of the claims of the specification thereof, it will be unnecessary for us to enter into any further description of it. We do not, however, confine our invention to this particular construction of roller, as we intend to employ plain cylinders, made as is shown at B in fig. 6 of the drawings, so long as these cylinders are made of proper materials and in a suitable manner for the purpose of operating with the mercury in the method as herein explained.

In the drawings, A denotes the frame of the machine. B and C are two cylinders or rollers, whose journals, or shafts c d are supported in suitable boxes a a, b b. The boxes b b of the shaft d of the roller C are movable, or are to be supported so as to be capable of sliding toward and away from the boxes a a, and they are provided with springs e e, by which they are pressed toward the said boxes a a, in order that the roller C may touch and properly adjust itself relatively to the roller B while the two may be in operation. Underneath each of these rollers is a trough to hold mercury, the same being placed so as to enable the roller to revolve within the mercury when it is in the trough.

The trough, shown at D, may extend up between the two rollers in manner as represented in fig. 6. The bottom of such trough may constitute the top of a heating-box or chamber, E, arranged underneath the trough and destined to receive steam or heated air for the purpose of heating the mercury and the rollers in order to prevent the pulp or the water from freezing upon the rollers while the surrounding atmosphere may be at or below a freezing temperature. This heating of the mercury and the rollers also serves to facilitate their operations and the amalgamation of the metal of the ore.

Between and above the rollers B C is a hopper, F, provided with an induction spout or chute, G, the latter being secured to the top of a cap or cover, H, which extends over and about the rollers in manner as represented in the drawings.

Furthermore, the shafts c d of the two rollers B C have a train of spur-gears, I K, applied to them, the same being in order that one roller may be revolved in a direction the reverse of the other. To the shaft of each roller B C we affix a grooved cam, L, the groove of whose periphery is so formed as to cause the roller, while in revolution, to have a reciprocating endwise movement. An arm, M, extends from the frame A into such grooves of the cam, such arm, with the cam, serving to produce the endwise movement of the roller while such roller and the cam may be in revolution.

Two scrapers, N N, arranged against opposite ends of the trough B, and with their edges against the peripheries of the two rollers B C, operate to remove the amalgam from the rollers and cause it to fall upon a riffle, O, arranged within the frame A and underneath the trough. The riffle, at its lower end, discharges into a spout or receiver, P. For supplying the riffle with water we employ a pipe or conduit, x, arranged at its upper end as shown in fig. 6; and for discharging from the riffle and the receiver P the waste ore or tailings we make an opening, y, in the end of the frame. The amalgam will gather in the receiver P, the tailings being carried off through the said opening y.

In order to facilitate the amalgamation of the metal we also employ, in connection with each of the main rollers B C, an auxiliary or smaller roller, R, which we arrange with respect to the main roller in manner as represented in figs. 1 and 6. A trough for holding mercury may be also applied to each of the said auxiliary rollers.

The principle of our machine is to be found in the employment of one roller or cylinder, a trough of mercury, and a scraper, or means of removing the amalgam from the surface of the cylinder. Although we have represented this, we have also shown two cylinders B C or rollers, arranged as described, as when they are so employed they not only perform the functions of two rollers so far as taking up the mercury from the trough is concerned, but they operate to evenly spread the mercury upon their surfaces and regulate the thickness of the films of it thereon.

Another mode in which we have contemplated the construction of our machine with the two cylinders B C is to employ two separate mercurial troughs, one to each cylinder, with a space between them. The cylinders are to revolve toward each of their upper surfaces. The scrapers in this case would be arranged in the space between the troughs, and there should be a sufficient space between them for the escape of the amalgam and tailings, which, in this case, would fall between the rollers.

In the operation of this machine the ore in the state of pulp is to be fed into the hopper F by means of the spout G, and so as to be delivered on and between the rollers B C while they may be in revolution in the mercury contained in the trough or troughs D.

The mercury having an affinity for the surfaces of the rollers will be taken up in a thin film on each of them, and in this state will be run in contact with the particles of the ore. The rollers revolving closely together the ore will not pass down between them, but will be agitated by them and the water flowing into the hopper. The films of mercury will extract the metal from the ore and carry it over in a state of amalgam to the scrapers, which will remove the amalgam from the rollers, it being discharged upon the riffle and into the trough at the bottom thereof.

The lateral or endwise motions of the rollers not only prevent their surfaces from becoming worn unevenly, but materially assist or facilitate the amalgamation of the metal with the mercury.

We claim as our invention a combination consisting not only of one or more rollers and one or more troughs of mercury or for holding mercury, but of one or more scrapers (or their equivalents) for removing the amalgam from the surface or surfaces of such roller or rollers, the whole being substantially as described.

We also claim the arrangement of two rollers and their mercury-trough so that the said rollers while in revolution may take up the mercury from the trough, and by their combined action press it against or cause it to adhere to and be spread evenly on their surfaces.

We also claim the construction of the mercury-trough so as to extend up between the two rollers and guide the mercury up to their bite while they are in revolution, the same being as exhibited in fig. 6.

We also claim the combination of the heating-chamber E, or a means of heating the trough of mercury, or the same and its roller or rollers, with the said trough, the roller or rollers, and the scraper or scrapers hereof, as specified.

We also claim the arrangement of the auxiliary rollers R R with the main rollers B C, their scrapers, and mercury-trough, as explained.

We also claim the combination, as well as the arrangement, of the riffle O with the trough D, one or more rollers B C, and one or more scrapers N N.

We also claim the combination of mechanism for imparting to either or both of the rollers B C endwise movements, under circumstances as set forth, with such rollers, the mercury-trough, and the scrapers, or their equivalents, the whole being substantially as specified.
